F. GARACHON.

LOCK.

No. 9,070.

Patented June 29, 1852.

UNITED STATES PATENT OFFICE.

FRANCIS GARACHON, OF NEW YORK, N. Y.

LOCK.

Specification of Letters Patent No. 9,070, dated June 29, 1852.

To all whom it may concern:

Be it known that I, FRANCIS GARACHON, of the city, county, and State of New York, have invented a new and useful Improvement 5 in Locks; and I do hereby declare the following to be a full and clear description of the same.

The nature of my invention consists in the arrangement of the lock, a check lever, and 10 its accessories for latching and unlatching the bolt relatively to a check lever for locking the revolving plate, whereby the auxiliary key acts upon the former by being lifted endwise and upon the latter by its 15 bit when revolving in the usual manner.

But to describe my invention more particularly, I will refer to the accompanying drawings forming a part of this schedule, the same letters of reference wherever they 20 occur referring to the same parts.

Figure 1, is a view of the face of the lock, showing the two independent keyholes. Fig. 2, is a view of the face of the lock, having the cap plate removed, and showing the bolt 25 thrown back, and by the dotted outline of the key in the tumbler, and direction of the arrow, the position for throwing the bolt. Fig. 3, is a front view of the same, showing the position of the bolt as thrown forward, 30 and position of the key and tumbler for throwing it back. Fig. 4, is a representation of an inner cap plate secured over the tumbler, check lever, &c. Fig. 5, is a representation of the bolt. Fig. 6, is a representation 35 of the edge of the bolt, showing the position of the check spring underneath it. Fig. 7, is a face view of the check spring. Fig. 8, is a view of the clasp for the end of the bolt to run in, having the cap removed so as to 40 exhibit the position of the check spring under the bolt, and check spring lever for operating it. Fig. 9, is a sectional view of the front end of the clasp, showing the check spring lever, and key and wards of the check 45 key, through the line x , x , Fig. 2. Figs. 10 and 11, are views of the upper and lower plates of the revolving tumbler, Fig. 11, showing the arrangement of the wards. Fig. 12, is a cut sectional view of the tumbler, 50 through the line x^2 , x^2 (of Fig. 11) with the stem of the revolving key. Fig. 13, is a view of the bolt key.

Letter A, A, case of the lock.

B is the outer cap plate of the lock, and 55 B', is the inner cap plate secured over the

tumbler, &c., and through which are cut key holes for the bolt key and check key.

C, is the bolt. This bolt is made with two or more prongs as may be required. Through the face of it is cut an ∞ shaped slot D, for the insertion of a port or stud E, on the main check F, for holding the bolt when either projected out or in, and which is held securely in position by the main spring G, resting on the back of it, and secured at the opposite end by a screw bolt to the plate of the lock. On the back end and lower side of the bolt, where it enters the clasp, is also a small check stud H, (see Fig. 6, and dotted outline in Fig. 5), 70 and also a notch J, cut in the edge of it for the key to operate against, in throwing the bolt out or in.

Letter K, is the tumbler. This tumbler is made from two plates of metal, and between which the wards L, for the bolt key are arranged, and secured to the lower plate K². These wards are put together so as to form a figure 5, and by their position prevent the admission of a pick, or other instrument, except the proper key, to operate on the notch J, in the bolt for throwing it. 75

Letter M, is the stem of the tumbler, which is surrounded by a square box N; and P, P, P, are studs, and screw holes for 80 securing the upper and lower plates of the tumbler together.

Letter R, is a small half circular notch, 90 cut in the edge of the lower plate K², of the tumbler, for the purpose of holding it, by means of the lever S, and spring S², at the lower side of the tumbler, and attached to the plate or case A, when the revolving key T, has exposed the keyhole of the tumbler for the admission of the key U. Letter V, is a small check pin inserted in the face of the plate K², of the tumbler. (See Figs. 11 and 12, and dotted outlines of it in Figs. 2 and 3 in the tumbler.) This pin 100 when the tumbler is revolved (in the direction of the arrow in Fig. 2), by the bolt key, to project the bolt, is brought around so as to fall or spring into the notched end of the check lever W, and thereby prevent the bolt key from being withdrawn from the lock till the check key Y, has been inserted to raise the back end of the check lever W, to allow the key and tumbler to rotate forward. This check lever is secured 105 to the plate A, by a fulcrum W², having its 110

back end extending across the wards of the check key, and held down by means of a spring Z.

Letter a^2 , is the cap of the check key 5 wards, and through which the check key Y, is inserted on the stem e^2 . In the front end of this cap plate a^2 is a small slot and opening f^2 , in which rests the back end of the check spring lever g^2 . This lever, (see Fig. 10 9), is secured by a fulcrum screw h^2 , to the front end of the clasp k^2 , for the bolt, and has its back end bent in such a manner as to enter the small slot and opening f^2 , in the cap a^2 , that the ward of the check key Y, 15 may raise it, for the purpose of depressing the opposite end inserted in a hook or bracket m^2 , on the lower side of the check spring n^2 . This spring is secured to the plate A, of the lock, by means of screws, 20 directly under the bolt, and is bent in such a manner, that its back end, resting in a groove in the clasp for the bolt, is always pressing against its lower face, so that when the bolt is projected forward, the stud H, 25 (see Fig. 6) enters the opening p^2 , in the back end of the spring, and thereby preventing the bolt from being thrown back except the check key is inserted to release it. Letters r^2 r^2 &c., are representations of 30 screw holes, and studs, for bolting or screwing down the inner cap plate B', and outer plate B to the case A.

The operation of this lock is that when it is desirous to lock it, is to insert first the 35 key T, and on turning it, the small projection on its lower edge falls into a hole in the box N, of the tumbler (see Fig. 12), and thereby causes the tumbler to turn with it till the check lever S, falls into the half 40 circular notch R, when it is stopped. The key T, is now withdrawn and the bolt key U, is inserted, and being turned in the direction of the arrow in Fig. 2, falls into the notch J, and lifting the check stud E, attached to the 45 check F, from the check in the end of the slot D, projects the bolt forward, and at the same time locks the tumbler, so that it can not move back or forward, to withdraw the key, by means of the forked end of the 50 check lever W, clasping the pin V (see Fig. 3), in the upper face of the plate K² of the tumbler. In this position the check key Y, is inserted, and turned on the stem, first half way around, so that the ward can act 55 on the back end of the lever W, to re-

lieve the pin V, and allow the tumbler to move forward, so that the bolt key may be withdrawn, and at the same time allow the stud H, on the lower and back end of the bolt to enter the hole p^2 in the check spring n^2 . When this is done the bolt and check keys are withdrawn, and the revolver key T, is inserted, and turned, so as to conceal the wards of the lock under the plate B, and is then withdrawn also, leaving only the 65 opening around the stem as the means of access to the interior of the lock. To return the bolt, the key T, must again be inserted, and turned as before described to expose the keyhole, for the key U, which on the 70 withdrawal of the key T, is introduced, and turned in the direction of the arrow (in Fig. 3) till it falls into the notch J, to lift the stud E, out of the check notch, in the slot D, but in which position the bolt can 75 not be shot back in consequence of the stud H, being in the hole p^2 , of the check spring n^2 . To release this, the check key Y, is inserted, and when turned half around on its stem, it releases the pin V, from the forked 80 end of the check lever W, and then by an upward or backward motion given to the key Y, as if about to withdraw it from the lock, the upper end of the ward of the key is forced (see Fig. 9) through the opening in the plate a^2 , of the slot f^2 , against the bent end of the check spring lever g^2 , so as 85 to lift it, and thereby depress the end of the check spring, so as to release the stud H, and allow, (the check key being retained 90 in that position all the while,) the bolt key to be turned so as to shoot the bolt back, when the bolt key and check key may be withdrawn.

Having now described my invention, I 95 will proceed to state what I claim, and desire to secure by Letters Patent of the United States—

The arrangement of the lever g^2 , and its accessories for latching and unlatching the 100 bolt relative to the lever W, for locking the revolving key plate, whereby the auxiliary key acts upon the former by being lifted endwise, and upon the latter by its bit, when revolving in the usual manner, substantially as set forth. 105
